LUDWIG SCHMIDT, OF ST. LOUIS, MISSOURI, ASSIGNOR TO ESSMUELLER MILL FURNISHING COMPANY, OF ST. LOUIS, MISSOURI, A CORPORATION OF MISSOURI.

GRINDING ROLL FOR FLOUR MILLS.

Application filed June 13, 1923. Serial No. 645,169.

To all whom it may concern:

Be it known that I, LUDWIG SCHMIDT, a citizen of the United States, residing in the city of St. Louis and State of Missouri, have invented new and useful Improvements in Grinding Rolls for Flour Mills, of which the following is a specification.

This invention relates to grinding rolls and a method of preparing the surfaces of the same.

In the reduction of wheat to flour, corrugated rolls are employed in reducing the grain down to a certain stage in which middlings are produced, the corrugated rolls being usually referred to as the "break rolls." The middlings are composed of the hard granular portion of the grain, and the finer grades of flour are made from them. In their reduction, smooth rolls are employed.

The ordinary arrangement of grinding or reducing rolls involves two rolls set in close proximity to each other, one of the rolls being run at a slightly increased speed relative to the other.

Originally, in the reduction of middlings, smooth and highly polished rolls were employed. It was soon found, however, that notwithstanding the differential rate of speed at which the rolls were run, the broken particles of grain did not pass readily between the rolls, as the latter were too smooth to bite or engage the particles of grain and cause them to pass between the rolls.

To overcome this disadvantage, rolls having very fine corrugations were substituted for the smooth rolls, at least at the head of the middlings reduction system. Not only are the finest practicable corrugations in such a roll too coarse to reduce the middlings in the manner desired, but it has been found to be almost impossible to secure accurate or uniform corrugation of the roll, due to mechanical reasons not necessary to set forth here.

To obviate the use of finely corrugated rolls, a method was devised for producing rolls with a dull finish instead of the highly polished surface which had previously characterized the smooth roll. The dull finish roll has been very extensively used, and, while it is an improvement over the polished roll, or the corrugated roll, it still presents the objection of being too smooth to cause

the proper engagement and feed of the grain particles between the rolls.

According to this invention, I provide for imparting a very fine degree of scratching to the surface of the roll, so that while its surface is relatively much rougher than that of a roll with a dull finish, such surface is much smoother than that of a roll having the finest degree of corrugation which it has been found practicable to produce.

According to one way of practicing my invention, the surface of the roll is smoothed off by an emery wheel in the usual manner. Thereafter, I apply to the surface of the roll the flat side of a relatively small wheel of any suitable abrasive material, such as emery, carborundum, or the like, the plane of the side of the wheel applied to the roll forming a tangent with the periphery of the roll, and the axis of said wheel lying at an angle to a plane cutting the axis of the roll. The roll is then revolved and simultaneously moved endwise through the medium of a lead-screw, and the grinding wheel in contact with the surface of the roll is also simultaneously revolved, with the result that the entire surface of the roll is subjected to the abrasive or grinding action of the wheel. The surface of the roll will, by this means, be scratched in a uniform manner, the coarseness of the abrasions produced on the surface of the roll corresponding, of course, to the coarseness of the grain of the material of the grinding wheel. The scratched surface of the roll will present a series of wave-like or billowy formations, which change in appearance and relative location according to the angle of vision, and the character and extent of which may be varied by varying the inclination of the axis of the grinding wheel relative to a selected plane cutting the axis of the roll.

Such method of scratching the surface of the roll possesses the advantage that it may be performed with relative rapidity. The scratching of the surface by grinding leaves the roll true throughout its entire surface, as the roll is not subjected to a bending pressure, as is the case where it is attempted to corrugate the roll. Furthermore, as the relative positions of the roll and grinding disk are fixed during the operation, and as

- the relative rates of movement of the grinding wheel and roll, and the speed at which the roll is advanced, are unchanged during the scratching operation, it follows that the 5 geometrical figures formed by the abrading points of the grinding wheel are reproduced with exact uniformity throughout the whole operation, but, owing to the differential existing between the speed of rotation of the 10 roll and that of the grinding wheel, and to the fact that the roll is both rotated, and advanced in a horizontal plane, the myriads of lines scratched on the surface of the roll, or the figures formed by said lines, are caused 15 to progressively overlap, or intersect, each other, so that no one portion of the surface of the roll can, by any possibility, receive a greater degree of abrading action than another portion.
- 20 A further advantage of this system of scratching the surface of the roll is that the scratched lines have a general curvilinear extension lengthwise of the roll, or, in other words, parallel with the axis of the roll, as 25 distinguished from an extension approximating parallelism with the direction of rotation of the roll, so that the maximum frictional engagement of the surface of the roll with the grain particles is thereby afforded.
- 30 In order that a correct idea may be gained of the degree of scratching employed, it may be stated that to the casual touch or feeling of the roll, its surface would appear smooth, the scratched lines being exceedingly minute, and the depth of the abrasion infinitesimal in extent.
- 35 In order that the invention may be fully understood, I have illustrated, in the accompanying drawings, an arrangement of apparatus by means of which the surface of a grinding roll may be etched in the manner herein described.
- 40 In said drawings—
- 45 Figure 1 is a cross-sectional view through a grinding machine provided with the means which I employ for practicing my improved method of finishing the surface of the roll;
- 50 Figure 2 is a view in front elevation showing a portion of a roll with a grinding disk applied thereto, the latter being sectioned from the rest of the grinding mechanism; and
- 55 Figure 3 is a view on an enlarged scale illustrating a portion of the surface of the roll after it has been scratched according to my method. This illustration, however, is suggestive rather than technically accurate.
- 60 Referring now to the drawings, the numeral 1 indicates the bed of a grinding machine of ordinary construction, the upper side of which provides guide-ways 2, on which is slidably mounted a carriage 3, which is provided at its upper ends with uprights 4, provided with the usual means for 65 rotatably supporting a roll 5. Said means

involves a rotatable head having a pulley 6, by means of which the roll 5 may be rotated through the medium of a belt 7. The carriage 4 is provided on its underside with a depending casting 8, which has, at its lower end, an interiorly screw-threaded bearing 9, which is in screw-threaded engagement with the lead-screw 10, extending longitudinally of the machine and rotated in the usual way to cause the carriage 4 to travel back and forth on the ways 2.

Extending from the rear of the bed 1 is a bracket 11, which supports standards 12, having rotatably mounted in their upper ends an emery wheel 13, driven by a belt 14 and pulley 15, and which is movable into and out of contact with the object to be ground.

So far, the machine described is of the usual construction and involves no element 85 of novelty. Heretofore, the practice has been to mount the roll 5 on the bed 1 and to move the same back and forth over the ways 2 while its surface was in contact with the rapidly rotating emery wheel 13. This resulted in imparting a smooth surface to the roll 5, and unless special means were utilized to impart a dull finish to the surface of the roll, the treatment with the emery wheel 90 would result in imparting a high degree of 95 polish to the roll. After the roll has been smoothed by the emery wheel 13, the latter is moved out of contact with the surface of the grinding roll 5, and the surface of the latter is then finished according to the 100 method of the present invention.

For the purpose of practicing my improved method, I mount on the front of the machine, centrally of its length, a bracket 16, in which are mounted four or more adjusting screws 17 which support, at their upper ends, a frame 18, having rotatably mounted therein a spindle 19, on which is secured, between the side members of the frame, a pulley 20, and at its ends, a grinding wheel 21. The pulley is driven from any suitable source of power by a belt 22. The height of the frame 18 relative to the axis of the roll 5 may be varied by adjusting the height of said screws. Nuts 23, on screws 17, support the base of the frame 18, and act also as clamping members. I also provide means for permitting the inclination of the axis of the spindle 19 relative to the axis of the roll 5 to be varied, and, in the present instance, this is effected by forming rounded heads 24 on the ends of the screws 17 which engage in large apertures 25 in the base of the frame 18. By lowering or raising one or the other of the screws, 110 or by raising one and lowering the other, the angle of inclination of the spindle 19 to the axis of the roll 5 can be changed at will, 115 as will be understood.

The construction illustrated for permit- 120

ting the adjustment of the height and angular inclination of the frame 18 is more or less conventional, and it will be understood that any preferred way of mounting the frame 18 may be employed.

In applying the grinding wheel 21 to the surface of the roll 5, the plane of the operative face of the grinding wheel, indicated by the line 26, is positioned at right angles to a radius 27 of the roll 5, forming an angle with a plane cutting the axis of said roll, and the height of the grinding wheel is so adjusted that its line of contact with the surface of the roll, indicated by the line 28, in Figure 2, is between its periphery and axial center. The length of this line of surface contact between the grinding wheel and roll may be varied from zero, the periphery of the grinding disk, to the maximum, which would be the line of contact between the surface of the roll and the face of the grinding disk, passing through the center of the grinding disk. In such case, of course, the full width of the grinding disk would then be in engagement with the surface of the grinding roll. In this latter position, the grinding disk would operate to scratch circular lines on the surface of the roll, owing to the symmetrical arrangement of the centers of the two rotating members.

In order to prevent this result, and to produce curved lines more nearly approximating to straight lines than to circular lines, I use a line of contact between the face of the disk and the surface of the roll, which, as stated, is between the periphery and center of the grinding disk. In preference, the length of this line is approximately one and one-half times the length of the pitch of the threads of the lead-screw 10, and I adjust the angle of inclination of the axis of the wheel to the axis of the roll so that the line of contact between the face of the grinding wheel and the surface of the roll is at right angles to a radius of the roll, forming an angle with a plane cutting the axis of the roll.

The relative speeds of rotation of the roll 5 and grinding wheel 21 may be varied at will, it being understood, of course, that the grinding wheel 21 rotates at a much higher rate of speed than the roll 5.

With apparatus arranged as described, the belts 7 and 22 are driven to rotate the roll 5 and grinding wheel 21, the grinding disk 13 having previously been moved out of contact with the roll 5. The lead-screw 10 is, of course, simultaneously rotated, with the result that the roll 5 is both rotated about its axis and moved longitudinally thereof.

At the completion of the movement of the roll in one direction, the machine is reversed and the roll moved in the opposite direction, still in contact with the grinding wheel

21, and this operation may be repeated three or four times. At the completion of the operation, the surface of the roll will have an appearance similar to that illustrated in Figure 3.

A roll having a surface of this character is ideal for the purpose of reducing middlings, as it is rough enough to engage and cause the prompt passage without slipping of the particles of grain between the rolls, and not sufficiently rough to cause the disintegrating or grinding action produced by corrugated rolls.

One of the decided advantages of my invention is the element of economy, both as to time and apparatus involved. A roll may have its surface finished, according to my method of procedure, on the average, in from fifteen to twenty minutes, and, of course, the provision and mounting of the grinding wheel is a matter of inconsiderable expense.

The character of the grinding wheel may be varied according to the degree of coarseness of the scratching desired on the roll, and any character of abrasive material, found suitable for the purpose, may be used in the composition of said wheel.

While I have shown and described the roll as being rotated and simultaneously moved longitudinally, while the grinding wheel is simply rotated, it will be obvious that the roll could simply be rotated, while the grinding wheel was both rotated and moved longitudinally. In other words, it is immaterial to the invention which of these members is moved longitudinally relative to the other.

I claim:

1. A cereal grinding roll having as its grinding dress, relatively short irregularly arranged grooves scratched therein and extending substantially longitudinally thereof.

2. A roll for milling wheat having its entire surface provided with extended and distinct lines of relatively short length ground-scratched therein.

3. A roll for milling wheat having its entire surface provided with distinct lines of scratches having a general longitudinal extension and of irregular length.

4. A roll for milling wheat having its entire surface provided with distinct lines of scratches having a general longitudinal extension and of relatively short length and irregular arrangement.

5. A roll for milling wheat having its entire surface provided with distinct lines of scratches, the said lines of scratches being curvilinear and of relatively short length and having a general extension longitudinal of the roll.

In testimony whereof, I have hereunto set my hand.

LUDWIG SCHMIDT.
